UNITED STATES PATENT OFFICE

LOUIS GOLDSTEIN, OF BROOKLYN, NEW YORK

DESIGN FOR A TEXTILE FABRIC

Application filed November 1, 1932. Serial No. 45,685. Term of patent 7 years.

To all whom it may concern:

Be it known that I, LOUIS GOLDSTEIN, a citizen of the United States, and residing at #1788 St. Johns Place, Brooklyn, New York, county of Kings, State of New York, have invented a new, original, and ornamental Design for a Textile Fabric, of which the following is a specification, reference being had

to the accompanying drawing, forming part thereof.

The accompanying drawing shows a piece of textile fabric embodying my design.

I claim:

The ornamental design for a textile fabric as shown.

LOUIS GOLDSTEIN,
